HANDLE FOR CANS

William T. Kahliff, Elyria, Ohio, assignor to The Chun King Corporation, Duluth, Minn., a corporation of Minnesota

Filed Apr. 10, 1961, Ser. No. 64,685

Term of patent 14 years

(Cl. D58—26)

FIG. 1.

FIG. 2.

FIG. 3.

FIG. 1 is a top plan view of a handle for cans showing my design;

FIG. 2 is a side elevational view thereof; and

FIG. 3 is a front elevational view thereof.

A side elevational view taken from the opposite side will appear substantially identical to FIG. 2. A bottom plan view thereof will appear substantially identical to FIG. 1.

I claim:

The ornamental design for a handle for cans, as shown and described.
